UNITED STATES PATENT OFFICE.

JOHN H. ROBERTSON, OF NEW YORK, N. Y., ASSIGNOR TO THE CHARLES SCOTT SPRING COMPANY, OF PHILADELPHIA, PENNSYLVANIA.

DESIGN FOR A CUSHION-PLATE FOR RAILROAD-RAILS.

SPECIFICATION forming part of Design No. 30,370, dated March 21, 1899.

Application filed February 20, 1899. Serial No. 706,260. Term of patent 14 years.

To all whom it may concern:

Be it known that I, JOHN H. ROBERTSON, a citizen of the United States, and a resident of New York city, New York, have invented **5** a new and useful Design for a Cushion-Plate for Railroad-Rails, of which the following is a specification.

My design for cushion-plates for railroad-rails is fully illustrated in the accompanying **10** drawings, in which—

Figure 1 is a perspective view illustrating my new design, and Fig. 2 is an edge view.

The essential feature of the design is a plate **15** having portions in the same horizontal plane at each end and between these portions a curved or arched portion.

In the drawings, *b b* represent the flat end portions of the plate, and *d* the curved or arched portion, *a a'* representing depending flanges or lugs at the ends of the plate. **20**

I claim—

The design for a cushion-plate for railroad-rails as fully described and as illustrated in the accompanying drawings.

In testimony whereof I have signed my **25** name to this specification in the presence of two subscribing witnesses.

JOHN H. ROBERTSON.
